COLLAPSIBLE TUBE

Christian Theodore Scheindel, Glen Gardner, N.J., and Herbert Eric Ralph Brown, South Acton, Mass., as signors to American Can Company, New York, N.Y., a corporation of New Jersey

Filed Feb. 13, 1963, Ser. No. 73,553

Term of patent 14 years

(Cl. D58—17)

Fig. 2.

Fig. 1.

The side of the tube not shown is substantially the same as the side elevational view of FIGURE 1.

We claim:

The ornamental design of a collapsible tube, substantially as shown and described.
